UNITED STATES PATENT OFFICE

149,715

DESIGN FOR AN ELECTRIC HEATER
HOUSING

George H. Wisting, Los Angeles, and Ray R. Conners, Jr., Beverly Hills, Calif., assignors to Scientific Heater Co., Inc., Los Angeles, Calif., a corporation of California

Application August 17, 1946, Serial No. 132,628

Term of patent 7 years

(Cl. D81—10)

To all whom it may concern:

Be it known that we, George H. Wisting and Ray R. Conners, Jr., both citizens of the United States, the former residing at Los Angeles, in the county of Los Angeles and State of California, the latter residing at Beverly Hills, in the county of Los Angeles and the State of California, have invented a new, original, and ornamental Design for Electric Heater Housings, of which the following is a specification, reference being had to the accompanying drawing, forming part thereof.

In the drawing:

Fig. 1 is a side perspective view taken from a somewhat elevated position, of an electric heater housing showing our new design;

Fig. 2 is a side elevational view of the electric heater housing of Fig. 1;

Fig. 3 is a top plan view of the heater housing; and

Fig. 4 is a bottom plan view of the heater housing.

We claim:

The ornamental design for an electric heater housing, as shown.

GEORGE H. WISTING.
